US0D1004901S

(12) **United States Design Patent** (10) **Patent No.:** **US D1,004,901 S**
(45) **Date of Patent:** **** Nov. 14, 2023**

(54) **LIFTING APPARATUS**

(71) Applicant: **Cranemasters, Inc.**, North Chesterfield, VA (US)

(72) Inventors: **Barry Isringhausen**, Providence Forge, VA (US); **Britt Calloway**, Midlothian, VA (US); **Jonathan Dip**, Glen Allen, VA (US)

(73) Assignee: **Cranemasters, Inc.**, North Chesterfield, VA (US)

(**) Term: **15 Years**

(21) Appl. No.: **29/837,842**

(22) Filed: **May 9, 2022**

Related U.S. Application Data

(60) Continuation of application No. 16/802,278, filed on Feb. 26, 2020, now Pat. No. 11,325,814, which is a continuation of application No. 16/213,415, filed on Dec. 7, 2018, now Pat. No. 10,577,226, which is a division of application No. 15/409,269, filed on Jan. 18, 2017, now Pat. No. 10,150,651.

(57) **CLAIM**

The ornamental design for a lifting apparatus, as shown and described.

DESCRIPTION

FIG. 1 is a front view of a lifting apparatus showing the claimed design; and,

FIG. 2 is a side view thereof.

The broken lines in the figures show portions of the lifting apparatus that form no part of the claimed design.

Portions of the lifting apparatus that are not shown form no part of the claimed design.

1 Claim, 2 Drawing Sheets
